CARGO BRACE STRUCTURE

Gerald D. Stough, Detroit, Mich., assignor to
 Whitehead & Kales Company, River Rouge,
 Mich., a corporation of Michigan

Application July 28, 1952, Serial No. 301,358

5 Claims. (Cl. 105—369)

1

The present invention relates to cargo brace structure comprising an elongated cross bar having at opposite ends thereof movable supporting heads adapted to fit into and interlock in openings provided in a pair of confronting spaced apart side walls. Cargo braces of this type are widely used in railroad cars, trucks, airplanes and the like, for bracing cargo against movement during transit.

The present invention is an improvement over the structure disclosed in my prior Patent No. 2,567,658 granted September 11, 1951. The present application is a continuation-in-part of my prior copending application Serial No. 238,099 filed July 23, 1951, and entitled "Cargo Brace Structure," now Patent No. 2,652,004, September 15, 1953.

It is an object of the present invention to provide a cargo brace comprising an elongated bar, a supporting head carried at one end of the bar with provision for rocking movement about an axis transverse to the length of the bar, and preferably for movement longitudinally of the bar, in conjunction with latch means operable to retain the movable head in supporting position against rocking movement, resilient means normally urging the latch means to operative position, and an actuator adapted to retract the latch means to permit swinging movement of the head.

More specifically, it is an object of the present invention to provide an apparatus of the character described, a pair of movable latch members mounted for rocking movement toward and away from the movable head, resilient means effective to urge both of said latch members toward the head, and an actuator pivoted to one of said latch members and engageable with a projection on the other latch member to effect swinging movement of both of said latch members away from said head.

Other objects and features of the invention will become apparent as the description proceeds, especially when taken in conjunction with the accompanying drawings, wherein:

Figure 1 is a plan view of a head supporting assembly carried at one end of a cross bar showing a portion of the supporting wall in section.

Figure 2 is a side elevation partly in section of the head supporting structure.

Figure 3 is a section on the line 3—3, Figure 2.

Figure 4 is a diagrammatic view illustrating a modified arrangement of latch release lever construction.

In the figures the cross bar is illustrated generally at 10 and as disclosed in my prior Patent

2

No. 2,567,658, may comprise a transverse horizontal web 12 having an upstanding flange 14 at one side thereof and a depending flange 16 at the other side thereof. If desired, the cross bar 5 may be completed by elongated wood bars respectively seated in the spaces between the central web 12 and the flange 14 and between the central web 12 and the flange 16. Cross bars of this type are well known and have the advantage of presenting wood exterior surfaces throughout their length for engagement with cargo.

At one end of the cross bar, and preferably at both ends thereof, there is mounted a supporting head 20 which as illustrated herein comprises 15 an elongated shank 22 terminating at its outer end in a laterally extending portion 24 provided at opposite ends thereof with a pair of upwardly curved hooks 26. Each of the hooks 26 is provided with a central thickened rib 28 and the 20 hooks are shaped to be received in openings 30 formed in the walls W. It will be observed that in operative position, as best seen in Figure 2, the ends of the hook portions 26 extend above the upper surfaces of the openings 30 and that 25 accordingly, the hooks 26 cannot be withdrawn from the openings except in conjunction with a swinging movement of the heads 20 in clockwise relationship relative to the cross bars 10.

The shanks 22 of the heads 20 are provided 30 with reduced portions 32 terminating adjacent the rear of the heads 20 in shoulders 34 and terminating forwardly of the heads in inclined shoulders 36. The inner or rear ends of the heads 20 are provided with transversely extending recesses 38 leaving abutment shoulders 40 for a purpose which will presently be described.

The transverse web 12 of the cross bar is provided with an elongated slot 42 in which the head 20 is movably received.

40 The movable head 20 is supported in a housing comprising a pair of side walls 44 and 46 interconnected by a rear wall 48. The side walls occupy lateral extensions in the slot 42 and extend both above and below the horizontal web 12 of the cross bar. However, the rear wall 48 is cut away and terminates in a shoulder 50, as best seen in Figure 2, on which the reduced portion 32 of the head is supported. A plate 52 is connected to the upper edges of the side walls 44 and 46 and overlies the intermediate portion of the shank 22 of the head 20. The housing structure is completed by an end plate 54 which may be welded or otherwise secured to the forward edges of the side walls 44 and 46 and the forward edge of the plate 52, as well as the adjacent end surfaces of

3

the cross bar. The end plate 54 is provided with a vertical slot 56 in which the forward end of the shank portion 22 of the head is movable.

With the parts in the position illustrated in Figure 2, it will be observed that weight applied to the cross bar 10 is supported by the hook portions 26 of the head, thereby tending to rock the head 20 in a counterclockwise direction about the axis established by shoulder 50. Such counterclockwise rotation however is prevented by engagement between the shank 22 and the plate 52 which engages the upper surface of the shank of the head outwardly of the shoulder 50. It will further be observed that the shoulder 50 of the rear wall 48 constitutes a fixed pivot support about which the head 20 may rock. Thus, in order to withdraw the head 20 from the openings 30 in the wall W the end of the cross bar structure is raised and the head 20 will thereupon rotate relative to the end of the cross bar in a clockwise direction, thus permitting withdrawal of the hooks 26 from the openings 30. When the head 20 is withdrawn from the opening 30 it is retained in assembly with the cross bar by engagement between the shoulder 34 and the rear wall 48 and also simultaneous engagement between the shoulder 49 and the inner end of the top plate 52.

It will also be observed that in the assembled relationship illustrated in Figure 2, the head is longitudinally movable with respect to the cross bar and will therefore accommodate relative approach and separation between a pair of opposed walls W.

In order to prevent inadvertent separation between the cross bars and the walls W, latch means are provided associated with the head which prevent movement of the head relative to the cross bar in the direction which is required to effect removal of the head from the openings in the wall. This means comprises a pair of latch members 60 and 62. The latch members are pivoted to a pivot pin 64 carried by the front plate 54 and have associated with the pivot pin 64 a spring 66 biasing the latch members to the latching position. The web 12 of the cross bar is provided with slots 68 through which the latch members extend providing for limited movement thereof, this movement however being sufficient to permit withdrawal of the hook portions 70 of the latch members from beneath the shanks 22 of the head 20.

In order to facilitate unlatching of the head to permit its withdrawal from the openings 30 in the wall W, special means are provided. This means is best illustrated in Figure 3 and comprises a lever 72 carried by a pivot pin 74 on one of the latch members, herein illustrated as the latch member 62. The other latch member 60 is provided with a projection 75 which is coplanar with the lever 72. The lever 72 has formed therein a recess 76 which receives the projection 75. When the operator wishes to release a cross bar from its interlocked position from a wall W, he first supports the weight of the cross bar so as to release parts of the head and latch mechanism for movement. Thereupon, he applies pressure to the lever 72. Pressure applied to the lever 72 tends to rock the latch member 60 in a clockwise direction and the reaction produces forces tending to rock the latch 62 in a counterclockwise direction. As a result, single application of pressure to the lever 72 will swing both latch members 60 and 62 outwardly so as to withdraw the hook portions 70

thereof from beneath the shank 22 of the head 20. Thereupon the cross bar may be raised and the head 20 may rock relative thereto in a clockwise direction withdrawing the hooks 26 from the openings 30.

Referring now to Figure 4 there is illustrated another embodiment of the present invention in which the latch levers 60 and 62 are as before described, but the latch release lever, herein designated 72a, is provided with a tooth 80 adapted to be received within a recess 82. Downward pressure applied to the lever 72a initially rocks the latch member 60 in a clockwise direction, the tooth 80 and recess 82 cooperating in the manner of gear teeth and tooth spaces during such movement of the latch member 60. Movement of the latch member 60 is arrested by engagement between the latch member and the side of the slot 68 and continued application of pressure to the lever 72a thereupon results in rocking movement of the latch member 62 to its release position.

The drawings and the foregoing specification constitute a description of the improved cargo brace structure in such full, clear, concise and exact terms as to enable any person skilled in the art to practice the invention, the scope of which is indicated by the appended claims.

What I claim as my invention is:

1. A cargo brace adapted to extend between a pair of spaced apart walls having aligned openings therein, said brace comprising a bar having a supporting head at one end thereof, said head comprising a shank and upwardly extending hook means located beyond the end of said bar and movable into and out of a selected opening in a wall, a pivot member on said bar engaging said shank intermediate the ends thereof to support said head for swinging movement about an axis transverse to said bar, abutment means on said bar overlying said shank intermediate said pivot member and the end of said bar to limit upward movement of said head, pivot means on said bar located above said head and intermediate said pivot member and the end of said bar, a pair of latch members carried by said pivot means for swinging toward and away from said shank, abutments on said latch members movable into positions beneath said shank to prevent downward swinging of said head, an actuating lever pivoted to one of said latch members, abutment means on said actuating lever and the other of said latch members operable to swing said other latch member to release position upon movement of said lever relative to said one latch member, said lever being disposed on said one latch member so that pressure applied thereto tends to swing said one latch member to release position.

2. A cargo brace as defined in claim 1 in which the abutment means on said lever and said other latch member are constructed to be equivalent to gears connecting said lever and member for swinging on their respective axes.

3. A cargo brace as defined in claim 2 comprising abutment means limiting outward movement of said latch members.

4. A cargo brace adapted to extend between a pair of spaced apart walls having aligned openings therein, said brace comprising a bar having a supporting head at one end thereof, said head comprising a shank and upwardly extending hook means located beyond the end of said bar and movable into and out of a selected opening in a wall, a pivot member on said bar engaging said shank intermediate the ends thereof

to support said head for swinging movement about an axis transverse to said bar, abutment means on said bar overlying said shank intermediate said pivot member and the end of said bar to limit upward movement of said head, pivot means on said bar located above said head and intermediate said pivot member and the end of said bar, a pair of latch members carried by said pivot means for swinging toward and away from said shank, abutments on said latch members movable into positions beneath said shank to prevent downward swinging of said head, said pivot means comprising a single pivot about which both of said latch members are mounted for swinging movement, an actuating lever pivoted to one of said latch members having a free end extending over said single pivot, rotary driving connections between said lever and said other latch member effective to swing said other latch member outwardly upon downward movement of said lever.

5. A cargo brace adapted to extend between a pair of spaced apart walls having aligned openings therein, said brace comprising a bar having a supporting head at one end thereof, said head comprising a shank and upwardly extending hook means located beyond the end of said bar and movable into and out of a selected opening in a wall, a pivot member on said bar engaging

said shank intermediate the ends thereof to support said head for swinging movement about an axis transverse to said bar, abutment means on said bar overlying said shank intermediate said pivot member and the end of said bar to limit upward movement of said head, pivot means on said bar located above said head and intermediate said pivot member and the end of said bar, a pair of latch members carried by said pivot means for swinging toward and away from said shank, abutments on said latch members movable into positions beneath said shank to prevent downward swinging of said head, said pivot means comprising a single pivot about which both of said latch members are mounted for swinging movement, an actuating lever pivoted to one of said latch members having a free end extending over said single pivot, rotary driving connections between said lever and said other latch member effective to swing said other latch member outwardly upon downward movement of said lever, an abutment limiting outward movement of said other latch member whereby pressure applied to said lever is effective after engagement between said abutment and said other latch member to swing said one latch member outwardly.
